UNITED STATES PATENT OFFICE.

MARION D. WORLEY, OF ST. STEPHEN, NEW BRUNSWICK, CANADA.

HAIR WAVER.

Application filed February 15, 1926. Serial No. 88,347.

My invention relates to hair wavers or crimpers, in which heat is imparted to the hair by means of a small receptacle carried by one of the arms of the device. In this 5 class of devices it is difficult to heat the iron uniformly, and thus the hair is burnt or liable to be rendered lifeless or injured by the same. By means of my device a uniform heat may be attained and for some time preserved.

A further object of the device is to so construct the same that it will be neat, durable, easily handled, cheaply manufactured, and can be filled with ease.

15 In the drawings forming a part of this specification, in which like symbols of reference represent corresponding parts in the several views:

Figure 1 is a perspective view of the device; and

Figure 2 is a view with the handles removed, to show the position of the arms when the device is in operation.

In the drawings the numeral 1 represents 25 one of the handles carrying the arms 3, which form a jaw within which the central arm 10, carried by handle 4, is adapted to operate. 5 is the hot water container or tank, the same being supported upon arm 10. 30 The arm 10 forms the bottom of the hot water receptacle. 6 is a screw cap on the tank for the purpose of filling the same; and 7 a nipple upon which the screw-cap 6 is screwed. 11 is a valve closing an opening in 35 the cap, the same having the side 12 connected to the cap, thus forming a spring valve for the escape of pressure. The object of the valve is to normally close the opening in the cap, but to permit escape of excessive 40 pressure due to steam.

8 are the outer waves on the bottom of the tank, the same receiving arms in the operation of the device.

The operation of the device will be apparent from the foregoing description. By 45 the use of my device the iron does not become smoked or otherwise soiled, which in turn prevents the hair being tarnished. The arms or prongs of the device do not become sufficiently hot to burn the scalp. Another 50 advantage is that the hair oils and dressings may be added to the iron direct, which adds a beautiful luster and permanency to the wave of the hair.

Having now fully described my invention, 55 what I claim as new, and desire to secure by Letters-Patent, is:—

1. A hair-waving device, consisting of handles hinged near their centres, prongs formed on one of the handles, and a tank 60 carried by the other handle and adapted to contain a heating liquid.

2. A hair-waving device, comprising a plurality of arms hinged near their centres, a liquid receptacle carried by one of the arms 65 said receptacle arm connected to the bottom of the receptacle, a plurality of recesses formed on the bottom of the receptacle, and prongs formed on the other arm and adapted to be received in the recesses of the receptacle.

3. A hair-waving device, comprising a pair of arms hinged near their centres, a liquid receptacle carried by one of the arms, an inlet in the receptacle having a valve for 75 escape of excessive pressure, recesses on the bottom of the receptacle, and prongs formed on the other arm and adapted to be received in the recesses of the receptacle.

4. A hair-waving appliance, comprising 80 a hot-water receptacle having a waved surface, a handle member rigidly carried by said receptacle and extending from one side thereof, a lever member intersecting and pivoted to the handle member, and a pressure device carried at one end of the lever member and adapted to press the hair against the waved surface of the receptacle 85 when the opposite end of the lever member is pressed towards the outer end of the handle member.

5. A hair-waving appliance, comprising a hot water receptacle having a hollow rib upon one face, a handle member rigidly carried by said receptacle and extending from one side thereof, a lever member intersecting and pivoted to the handle member, and a bifurcated pressure member carried at one end of the lever member and adapted to engage upon opposite sides of the rib and to 95 press the hair over the said rib, when the opposite end of the lever member is pressed towards the outer end of the handle member.

In testimony whereof I affix my signature.

MARION D. WORLEY.
